UNITED STATES PATENT OFFICE.

FRANCIS E. L. HARRIS, OF ALDERLEY EDGE, ENGLAND.

APPARATUS FOR CLEANING LARGE PANES OF GLASS.

No. 880,660.

Specification of Letters Patent.

Patented March 3, 1908.

Application filed November 12, 1906. Serial No. 343,121.

To all whom it may concern:

Be it known that I, FRANCIS ELDRED LODGE HARRIS, a subject of the King of Great Britain and Ireland, and resident of 5 Alderley Edge, in the county of Chester, England, architect, have invented a certain new and useful Improved Apparatus for Cleaning Large Panes of Glass.

This invention relates to a new or improved apparatus for cleaning large panes of glass such as those used in shop windows, show cases and the like though it may be applied to smaller panes, the object being to remove the water of condensation also which 10 may form upon either the inside or the outside of the pane.

My invention will be fully described with reference to the accompanying drawings in which 15 Figure 1 is a transverse vertical section of an apparatus constructed in accordance with my invention while Fig. 2 is a partial plan of same partly in section.

In carrying out my invention I arrange 20 either at the inside or outside of the pane *a*, as may be required, and at either end or side of the latter a suitable guide *b* of wood or metal or a combination of each, such guide preferably having a longitudinal groove *c*. 25 Extending across the window I employ a lath, bar or rod *d* of a suitable character and formed of wood or metal or a combination of each or of other material or materials most suitable for the purpose, the front edge *e* of 30 which projects towards the window pane leaving a small space between it and the glass *a*. This lath may have suitably secured to 35 it at its front edge a sheet or pad of felt *f* or other suitable material which is preferably arranged upon a base *g* of india rubber or 40 other elastic or resilient substance and which is adapted so as to press tightly against the window pane and yet to give way to any 45 inequalities of the latter. The pad of felt and rubber may be secured to the lath by the free ends of each being passed into a 50 groove formed at the front edge of the lath the required grip to hold it in place being secured by a covering strip *i* through which is passed screws *j*, bolts or the like. At the ends the lath is provided with metal studs *k*

which extend into the grooves *c* of the vertical guides *b* and for this purpose such ends are protected by metal plates *l* to reduce wear, the studs being secured thereto or 55 formed integral therewith. Through these studs pass the supporting and pulley cords *m*.

The cords are not passed directly through the studs but as will be seen by Fig. 1 they are passed indirectly through so as to act as 60 a support for the lath and at the same time by the top and bottom portions of the cord not being in alinement to cause the felt pad to be kept tightly against the window when the cord is pulled for cleaning purposes. 65

The lath or rod *d* is suspended by the cord or rope, chain or the like *m* at each end, each rope or cord passing over a guide pulley or pulleys arranged in or adjacent to the guides and terminating in counter-balance weights 70 *n* adapted to rise and fall in a casement *o*, if desired. The ropes are also continued downwards and passed round suitably arranged guide pulleys *p* after which they are brought together near the center of the lower portion 75 of the window. Normally the lath rests against two projecting studs *q* near to the top end of the window pane with its rubbing or cleaning edge slightly removed from the glass to allow of the rubbing material becoming 80 dry as will be seen from the broken lines in Fig. 1 and in which position it is held by the counter-balance weights *n*. By pulling the ring or handle secured to the cords *m* or by winding the drum or winch at the lower end 85 of the pane the rubbing edge of the pad is immediately brought in contact with the face of the glass *a* by a slight lever action set up by the position of the ropes or cords in passing through the lath as previously described and 90 is brought down the face of the glass so as to clean the window or remove water of condensation, while on releasing the handle the counter-balance weights pull the lath to the top of the glass again. This operation may 95 be repeated as often as necessary.

What I claim as my invention and desire to secure by Letters Patent is:—

An apparatus for cleaning large panes of glass comprising a lath, a pad arranged at the 100 forward edge of the lath, brackets in each end of the lath provided with reduced ex-

tensions, each extension being provided with three transversely alining openings, guides arranged at each end of the lath said guides having grooves to receive the reduced extensions of the brackets, and operating cords for the lath, a cord passing continuously through the alining openings of each bracket.

In testimony whereof I have hereunto set my hand in the presence of two witnesses.

F. E. L. HARRIS.
